DIFFUSION PLATE FOR BLOOD ANALYSIS

Kingdon Lou, Tustin, Calif., assignor to
ICL Scientific, Fountain Valley, Calif.

Filed Mar. 29, 1971, Ser. No. 129,277

Term of patent 14 years

Int. Cl. D24—02

U.S. Cl. D16—1 R

FIG. 1 is a perspective view of a diffusion plate for blood analysis and cover showing my design applied thereto;

FIG. 2 is a top plan view of the diffusion plate and cover;

FIG. 3 is a side elevation of the plate taken in the direction of the arrow 3 of FIG. 1;

FIG. 4 is an end elevation of the plate taken in the direction of the arrow 4 of FIG. 1;

FIG. 5 is a bottom plan view of the plate; and

FIG. 6 is an exploded view showing the cover removed.

I claim:

The design for a diffusion plate for blood analysis, substantially as shown.
